(57) **CLAIM**

The ornamental design for an ice skate blade measuring apparatus, as shown and described.

DESCRIPTION

FIG. 1 is a perspective view of the front of a fully assembled skate blade measuring apparatus in accordance with an embodiment of the invention.

FIG. 2 is a front elevation of a fully assembled skate blade measuring apparatus in accordance with an embodiment of the invention.

FIG. 3 is a rear elevation of a fully assembled skate blade measuring apparatus in accordance with an embodiment of the invention.

FIG. 4 is a left elevation of a fully assembled skate blade measuring apparatus in accordance with an embodiment of the invention.

FIG. 5 is a right elevation of a fully assembled skate blade measuring apparatus in accordance with an embodiment of the invention.

FIG. 6 is a top view of a fully assembled skate blade measuring apparatus in accordance with an embodiment of the invention; and,

FIG. 7 is a bottom view of a fully assembled skate blade measuring apparatus in accordance with an embodiment of the invention.

The broken lines in FIGS. 1 and 6 depict screw heads which are illustrative of environment and not intended to form a part of the claimed design.
